DESIGN FOR A SHOE

David Levin, New York, N. Y.

Application May 25, 1940, Serial No. 92,619

Term of patent 3½ years

To all whom it may concern:

Be it known that I, David Levin, a citizen of the United States of America, residing in city of New York, county of New York, and State of New York, have invented a new, original, and ornamental Design for a Shoe, of which the following is a specification, reference being had to the accompanying drawing, forming part thereof.

Fig. 1 is a side elevational view of a shoe showing my new design.

Fig. 2 is a top plan view thereof.

Fig. 3 is a bottom plan view.

Fig. 4 is a rear elevational view.

I claim:

The ornamental design for a shoe, as shown.

DAVID LEVIN.
